(57) **CLAIM**

The ornamental design for a motor car, as shown and described.

DESCRIPTION

1. Motor car

1.1 is a top plan view of a motor car showing my new design;

1.2 is a front elevation view thereof;

1.3 is a rear elevation view thereof;

1.4 is a right side elevation view thereof;

1.5 is a front and left side perspective view thereof;

1.6 is a front and right side perspective view thereof;

1.7 is a rear and left side perspective view thereof;

1.8 is a rear and right side perspective view thereof;

1.9 is a top, front, and left side perspective view thereof;

1.10 is a top, front, and right side perspective view thereof;

1.11 is a top, rear, and left side perspective view thereof; and

1.12 is a top, rear, and right side perspective view thereof.

Novelty resides in the shape and configuration of a motor car as shown in the reproductions.
